UNITED STATES PATENT OFFICE.

ARLINGTON MOORE, OF BOSTON, MASSACHUSETTS, ASSIGNOR TO CLARKE-MOORE CORPORATION, OF WILMINGTON, DELAWARE, A CORPORATION OF DELAWARE.

PAPER CONTAINER.

Application filed October 28, 1920, Serial No. 420,229. Renewed October 11, 1923.

To all whom it may concern:

Be it known that I, ARLINGTON MOORE, a citizen of the United States, residing at Boston, in the county of Suffolk, State of Massachusetts, have invented certain new and useful Improvements in Paper Containers; and I do hereby declare the following to be a full, clear, and exact description of the invention, such as will enable others skilled in the art to which it appertains to make and use the same.

The present invention relates to paper containers, that is, paper containers made of any suitable fibrous stock, whether paper or resembling paper, and particularly to such a container having a hinged cover. The container may be in the form of a can with a cylindrical side wall or any suitable polygonal form, wound or formed in any suitable way. The paper stock may be single or multiple ply, with or without incorporating a binder, and the container may be coated with paraffin or the like, or may have a paper cover or advertising label.

In accordance with one part of my invention the container has a cover provided with a hinge consisting of a roll which is spaced from the top of the cover, and a strip of any suitable material joining the roll and the cover. The roll is preferably integral with the container, and the strip joining the cover and the roll may be a separate section of stock or be formed of a continuing portion of the cover. When the cover is opened, the joining strip or section of stock folds back upon the roll and the latter is spaced from the top of the cover so that the joining section may be ample in length to permit the cover to open a sufficient amount.

The roll may be formed of a convoluted portion of the side wall of the container and the section of stock joining the cover and roll may extend into the convolutions of the roll. Whether or not the joining section is a separate piece of material, or consists of a continuing portion of the cover, the roll may be formed of a portion of the side wall of the container folded together with the terminal portion of the joining section, preferably folded upon or in contact with the joining section. Where the cover is flanged, the roll is formed of a portion of the side wall of the container folded together with an extended portion of the flange. Moreover, the roll may be subjected in forming to a high

pressure to render the folds thereof highly compressed and practically solidified. So treated, the roll becomes a rigid member firmly securing the cover and furnishing a substantial support to the cover when open. 60

Irrespective of the manner in which the roll is formed, or whether or not the cover is joined with the roll by a section of stock, or otherwise, the invention comprehends as another of its parts a paper container having a cover and a hinge therefor consisting of a roll which is spaced from the top of the cover and a strip joining the cover with the roll together with a bottom closure for the container consisting of a cap and a bead. 70 The cap is provided with a wall, and the bead is formed of folded portions of the wall of the cap and the side wall of the container. The walls of the cap and of the container have complementary recessed portions for interlocking them, and the folds of the bead are anchored in one of the recessed portions.

In the specific embodiment of the invention described hereinafter, the container has 80 a flanged cover. The roll is formed of a portion of the side wall folded together with an extended portion of the flange; and the bottom closure of the container consists of a cap having a wall folded inwardly together with the side wall to form a bead in contact with the cap. Both the wall of the cap and the side wall of the container have complementary recessed portions for interlocking them, and the folds of the bead are 85 anchored in the recessed portion of the wall of the cap.

In the accompanying drawings illustrating the invention in application, as an example, to a pocket tobacco can,

Fig. 1 represents in section and in perspective view a pocket tobacco can with a hinged cover, the raised position of the cover being illustrated in dotted outline; Fig. 2 is a view of the upper rear part of 100 the can showing the hinge; and Fig. 3 is a sectional detail of the hinge.

The container has a side wall 1 of curved formation flattened to fit the pocket, and has a flanged cover 2 and a bottom closure 3. 105 The cover 2 is provided with a hinge consisting of a roll 4 and a section of stock 5, joining the roll and the cover. The joining section 5 is cut from the flange of the cover and has an extended portion 7 which 110

is folded together with the portion 6 cut from the side wall of the container to form the roll 4. The roll 4 is spaced from the top 10 of the cover 2 so that when the cover is open as illustrated in dotted outline in Figs. 1 and 3, the joining section 5 is folded back upon the roll 4. The angularity of the cover with respect to the top of the container in the extreme open position depends upon the 15 length of the joining section 5, as well as upon the diameter of the roll 4, and may therefore be varied to secure any desired position of the cover when fully opened, consistent with its proper seating when closed.

15 The bottom closure 3 of the container consists of a cap 11 having a wall 12 which is folded inwardly together with the side wall 1 to form a bead 13 in contact at 14 with the cap. Both the side wall 1 and the wall of 20 the cap 12 are recessed as at 15 and 16 respectively and the folds of the bead are anchored in the recess 16 of the wall of the cap to secure them against displacement.

25 The roll is subjected in forming to a pressure of about from 4000 to 6000 pounds per square inch, under which it becomes highly compressed and practically solidified and the convolutions thereof are rigidly set. The roll thus formed and treated provides substantial fastening means for the cover and a firm support therefor in extreme open position.

Having thus described my invention, what I claim is:

2. In a paper container, a cover, and a hinge therefor comprising a roll spaced from the top of the cover and a strip joining the cover with said roll.
- 40 3. In a paper container, a cover, and a hinge therefor comprising a roll integral with the container and spaced from the top of the cover, and a section of stock joining the cover with said roll.
- 45 4. In a paper container having a side wall, a cover, and a hinge therefor comprising a roll spaced from the top of the cover and formed of a convoluted portion of said side wall, and a section of stock joining the cover with said roll.
- 50 5. In a paper container having a side wall, a cover, and a hinge therefor comprising a roll spaced from the top of the cover and formed of a convoluted portion of said side wall, and a section of stock joining the cover with said roll and extending into the convolutions thereof.
- 55 6. In a paper container having a side wall, a cover, and a hinge therefor comprising a roll spaced from the top of the cover and a section of stock joining the roll and the cover, said roll being formed of a portion of

said side wall folded together with the terminal portion of the joining section.

6. In a paper container having a side wall, a cover, and a hinge therefor comprising a roll spaced from the top of the cover and a section of stock joining the roll and said cover, said joining section consisting of a continuing portion of the cover and said roll being formed of a portion of the side wall folded together with the terminal portion of the joining section.

7. In a paper container having a side wall, a cover, and a hinge therefor comprising a roll spaced from the top of the cover and a section of stock joining the roll and said cover, said joining section consisting of a continuing portion of the cover and said roll being formed of a portion of the side wall folded together with the terminal portion of the joining section.

8. In a paper container having a side wall, a flanged cover; a hinge therefor comprising a roll spaced from the top of the cover and a section of stock joining the roll and said cover, said joining section consisting of an extended portion of the flange of the cover.

9. In a paper container having a side wall, a cover, and a hinge therefor comprising a highly compressed and practically solidified roll spaced from the top of the cover and a section of stock joining the roll and the cover, said roll being formed of a portion of the side wall folded together with the terminal portion of said joining section.

10. In a paper container having a side wall, a cover; a hinge therefor comprising a roll spaced from the top of the cover and a strip joining the cover with said roll; and a bottom closure comprising a cap having a wall folded together with said side wall to form a bead, said walls having complementary recessed portions for interlocking them, and the folds of said bead being anchored in one of said recessed portions.

11. In a paper container having a side wall, a flanged cover; a hinge therefor comprising a roll spaced from the top of the cover and a section of stock joining the roll and said cover, said joining section consisting of an extended portion of the flange of the cover; and a bottom closure therefor comprising a cap having a wall folded inwardly together with said side wall to form a bead in contact with the cap, said walls having complementary recessed portions for interlocking them, and the folds of said bead being anchored in the recessed portion of the wall of the cap.

In testimony whereof I affix my signature.

ARLINGTON MOORE.
